UNITED STATES PATENT OFFICE.

RENNIE G. LITTLE, OF MANCHESTER, NEW HAMPSHIRE.

PLUG.

1,322,493.

Specification of Letters Patent. Patented Nov. 18, 1919.

Application filed September 14, 1918. Serial No. 254,159.

To all whom it may concern:

Be it known that I, RENNIE G. LITTLE, a citizen of the United States, residing at Manchester, in the county of Hillsboro, and 5 State of New Hampshire, have invented new and useful Improvements in Plugs, of which the following is a specification.

This invention relates to internal combustion engines, particularly to igniting devices therefor, and has for its object the provision of a plug within which an ordinary spark plug is threaded and which is provided with a chamber communicating with the firing chamber of the engine cylinder through a pair of ports and also 15 through a valve controlled opening.

An important object is the provision of a device of this character which is so constructed that during the operation of the 20 engine a small portion of the explosive charge will be drawn into the chamber of the plug where it will be ignited and subsequently discharged into the firing chamber of the engine cylinder so as to insure 25 the ignition of a charge therein.

Another object is the provision of a device of this character which will be extremely simple and inexpensive in manufacture, highly efficient in use, durable in 30 service and a general improvement in the art.

With the above and other objects and advantages in view, the invention consists in the details of construction to be hereinafter 35 more fully described and claimed, and illustrated in the accompanying drawing, in which:—

Figure 1 is a sectional view through a portion of an internal combustion engine 40 showing my plug applied thereto and having a spark plug associated therewith.

Fig. 2 is a side elevation of the device detached and,

Fig. 3 is a detail cross sectional view 45 therethrough.

Referring more particularly to the drawing the letter A designates a portion of an internal combustion engine cylinder provided with the usual threaded opening B 50 for engagement of a spark plug.

My device is indicated as a whole by the numeral 5 and comprises a cylindrical body 6 externally threaded as shown at 7 for engagement within the opening B in the engine cylinder. At its upper end the body 55 6 is enlarged to provide an angular portion

8 engageable by a wrench for screwing the device into the engine cylinder. The junction of the enlarged angular portion 8 with the threaded portion 7 of the body defines a 60 shoulder 9 engageable upon the top of the cylinder casting. The bottom wall of the body 6 is provided with a central opening 10 forming a valve seat. The body 6 is provided with a bore 11 communicating with 65 the opening 10 and also communicating with a bore 12 of greater diameter formed in the angular portion 8. The bore 12 is internally threaded and is of the same diameter as the externally threaded portion 70 7 of the body.

A ball 13 is disposed within the lower end of the bore 11 and normally closes the central opening 10 in the bottom wall of the plug. The ball 13 is movable and has its 75 upward movement limited by a cross bar 14 extending across the intermediate portion of the bore 11. At opposite points, the lower portion of the body 6 is provided with ports 15 communicating with the bore 11. 80

In use, the device is threaded into the ordinary spark plug opening B and a spark plug C is threaded into the bore 12 whereupon its firing points will extend into the bore 11. On the compression stroke of the 85 engine piston the pressure of the charge upon the ball 13 will unseat the ball and will allow a portion of the compressed charge to enter the bore 11 through the central opening 10 in the bottom of the plug. When the plug C fires the charge within the bore 11 will be ignited and will flash through the ports 15, igniting the charge in the combustion chamber of the engine 90 cylinder.

From the foregoing description and a study of the drawing it will be apparent that I have thus provided what is in effect an auxiliary firing chamber within which a small portion of the charge will be initially ignited for producing and discharging into the combustion chamber of the engine a long hot flash which will be very effective in igniting the main charge. Furthermore, it will be noted that in view of the fact that only a small portion of the charge comes in contact with the firing points of the spark plug that fouling of the points of the plug will be reduced to the minimum and the efficiency of the plug will be consequently 100 increased.

While I have shown and described the

preferred embodiment of the invention, it will of course be readily understood that I reserve the right to make such changes in the form, construction and arrangement of parts as will not depart from the spirit of the invention nor the scope of the subjoined claims.

Having thus described my invention I claim:-

- 10 1. A device of the character described comprising a cylindrical body threaded for engagement within the spark plug opening of an engine, said body being adapted for the reception and connection of a spark plug, the lower end of said body forming a gas chamber and being provided with opposite laterally extending ports communicating with the bore thereof and with the combustion chamber of the engine, and a ball 15 movably disposed in an aperture in the lower end of said body and extending above the lower edges of said ports whereby to deflect through said ports burning gas ignited within said bore.
- 20

2. A device of the character described 25 comprising a cylindrical body externally threaded for engagement within the spark plug opening of an engine, the lower portion of said body being provided with a bore and its bottom wall being provided 30 with a vertical opening communicating with said bore and with the combustion chamber of the engine, the lower portion of said body being provided with lateral ports communicating with the combustion chamber 35 and with said bore, a ball disposed within said bore and normally closing said opening, said ball extending above the lower edges of said ports to serve as a deflector, means for limiting the upward movement of said 40 ball, the upper portion of said body being provided with a bore internally threaded for the reception of a spark plug, and said last named bore being of the same diameter as the externally threaded portion of said 45 body.

In testimony whereof I affix my signature.
RENNIE G. LITTLE.
